BLAST FURNACE

Henry W. Hochberger, Chicago, Ill., assignor to United States Steel Corporation, a corporation of New Jersey

Application October 30, 1957, Serial No. 693,466

2 Claims. (Cl. 266—31)

This invention relates to a blast furnace and more particularly to the utilization of the flue dust in a blast furnace. The blast furnace gas passes through a dust catcher where the flue dust is separated out and periodically recovered. After recovery it is generally sintered and charged into the furnace as part of its burden. It has been suggested in the patent to Dougherty No. 1,024,623 that the flue dust be returned to the furnace without sintering but the apparatus and method of doing this is such that it is difficult to retain the flue dust in the furnace.

It is therefore an object of my invention to provide apparatus for automatically charging flue dust into the furnace without sintering in such a manner that a large portion of the flue dust will remain in the furnace.

This and other objects will be more apparent after referring to the following specification and attached drawings, in which:

Figure 1 is an elevation, with parts broken away and shown in section, of the apparatus of my invention;

Figure 2 is a view taken on the line II—II of Figure 1; and

Figure 3 is a view taken on the line III—III of Figure 1.

Referring more particularly to the drawings, the reference numeral 2 indicates the top of a blast furnace having the usual big bell hopper 4 and big bell 6 mounted at the top thereon. The big bell 6 has a bell rod 8 fastened to the top thereof by which the big bell is raised into contact with the lower part of the big bell hopper or lowered to permit discharge of the burden thereon into the furnace. The burden of coke, iron ore and limestone is charged into the big bell hopper from the small bell in the usual manner. Four conduits 10 are connected to the top of the blast furnace 2 and the blast furnace gas passes upwardly therethrough to a dust catcher 12. Each pair of conduits 10 merge into a single conduit 14 so that there are two conduits 14 passing up alongside the dust catcher 12. A bleeder valve 16 is arranged at the top of each conduit 14. From the top of the conduits 14 the gas passes through branch passages 18 to the top of the dust catcher 12. The gas then passes downwardly through conical passage 20 of the dust catcher and upwardly

2

through passage 22 to takeoff 24. When the direction of gas travel is reversed at the bottom of passage 20 flue dust is separated out and falls into a plurality of conical hoppers 26 at the bottom of the dust catcher. Four such hoppers are shown and a conduit 28 is attached to the bottom of each hopper. Each conduit 28 has two branches 30 which lead to a secondary hopper 32 at the top of the blast furnace 2. Hopper 32 surrounds the hopper 4 and the bottom thereof is closed by big bell 6. The conduit branches 30 are arranged so that they pass into the hopper 32 approximately forty-five degrees apart.

The operation of my device is as follows:

The blast furnace gas passes continuously from the top of the blast furnace 2 to the dust catcher 12 where the flue dust is continuously separated out into the hoppers 26. From here the dust passes through conduits 28 and 30 to the secondary hopper 32. When the burden has been charged to the top of the big bell hopper the big bell 6 is lowered and the burden along with the flue dust in the hopper 32 passes downwardly into the furnace 2. The big bell 6 is then raised to close the hoppers 4 and 32 and the charge of coke, iron ore and limestone is charged onto the big bell 6 from the small bell (not shown) in the usual manner. The operation is then repeated.

While one embodiment of my invention has been shown and described it will be apparent that other adaptations and modifications may be made without departing from the scope of the following claims.

I claim:

- 30 1. In a blast furnace the combination comprising a dust catcher, a big bell, a main big bell hopper for receiving the furnace burden, a secondary big bell hopper on the outside of said main big bell hopper, said hoppers being open at the bottom and adapted to be closed by said big bell, means for delivering blast furnace gas from said furnace to said dust catcher, and means for delivering flue dust from said dust catcher to said secondary big bell hopper.
- 35 2. In a blast furnace the combination comprising a dust catcher, a big bell, a main big bell hopper for receiving the furnace burden, a secondary big bell hopper on the outside of said main big bell hopper, said hoppers being open at the bottom and adapted to be closed by said big bell, a conduit leading from said blast furnace to the top of said dust catcher for carrying blast furnace gas thereto, and a plurality of conduits leading from the bottom of said dust catcher to said secondary big bell hopper for carrying flue dust thereto at spaced points around its periphery.
- 40 3. In a blast furnace the combination comprising a dust catcher, a big bell, a main big bell hopper for receiving the furnace burden, a secondary big bell hopper on the outside of said main big bell hopper, said hoppers being open at the bottom and adapted to be closed by said big bell, a conduit leading from said blast furnace to the top of said dust catcher for carrying blast furnace gas thereto, and a plurality of conduits leading from the bottom of said dust catcher to said secondary big bell hopper for carrying flue dust thereto at spaced points around its periphery.
- 45 4. In a blast furnace the combination comprising a dust catcher, a big bell, a main big bell hopper for receiving the furnace burden, a secondary big bell hopper on the outside of said main big bell hopper, said hoppers being open at the bottom and adapted to be closed by said big bell, a conduit leading from said blast furnace to the top of said dust catcher for carrying blast furnace gas thereto, and a plurality of conduits leading from the bottom of said dust catcher to said secondary big bell hopper for carrying flue dust thereto at spaced points around its periphery.
- 50 5. In a blast furnace the combination comprising a dust catcher, a big bell, a main big bell hopper for receiving the furnace burden, a secondary big bell hopper on the outside of said main big bell hopper, said hoppers being open at the bottom and adapted to be closed by said big bell, a conduit leading from said blast furnace to the top of said dust catcher for carrying blast furnace gas thereto, and a plurality of conduits leading from the bottom of said dust catcher to said secondary big bell hopper for carrying flue dust thereto at spaced points around its periphery.
